COTTER STRAWN CHALFANT, OF EL PASO, TEXAS.

SPARK-ARRESTER.

No. 851,494.

Specification of Letters Patent.

Patented April 23, 1907.

Application filed April 3, 1906. Serial No. 309,698.

To all whom it may concern:

Be it known that I, COTTER STRAWN CHALFANT, a citizen of the United States, and a resident of El Paso, in the county of El Paso and State of Texas, have invented a new and Improved Spark-Arrester, of which the following is a full, clear, and exact description.

This invention is an improvement in spark arresters and has, among other objects, to provide a device of this character which will enforce the economical consumption of fuel, eliminate danger and discomfort caused by escaping sparks and cinders, and increase the efficiency of the locomotive by dispensing with the usual obstructing screens, nettings, etc. detrimental to good steaming qualities.

Another object is to provide a spark arrester which will not choke the draught in the smoke box and thereby cause the blowing of smoke and fire out through the fire box door into the cab; a condition to be contended with in the operation of certain forms of spark arresters hitherto devised.

The above objects are accomplished by my invention, one embodiment of which is hereinafter disclosed.

Reference is to be had to the accompanying drawings forming a part of this specification, in which similar characters of reference indicate corresponding parts in all the figures.

Figure 1 is a side elevation, partly in section, of my improvement as applied to a locomotive; Fig. 2 is a front sectional elevation on the line 2—2 of Fig. 1, looking in the direction of the arrow, and Fig. 3 is a section on the line 3—3 of Fig. 2, looking in the direction of the arrow.

Before proceeding to describe the invention in detail, the principle thereof will be stated. It is well known that if a mixed stream of gaseous and solid material, the latter being in a finely divided state, be introduced into a curved pipe, the solid particles will tend to collect against and follow along the outer wall thereof. Now, if suitable openings are provided along this wall of the pipe for the escape of the solid particles, they will, by virtue of their momentum and the pressure of the gases behind them, pass with a portion of the same through the openings and flow for a considerable distance into any suitable duct provided for their collection. This principle has been adopted in carrying out my invention, which may generally be stated to consist of a curved smoke

stack extending through the smoke box of the engine to within a short distance of a properly directed exhaust pipe, said smoke stack having suitable openings surrounded by a casing forming a spark chamber and conducting the sparks to the ash pan or fire box, preferably the latter.

The numeral 1 indicates a curved smoke stack as applied to an ordinary form of locomotive, said stack passing through the smoke box and terminating at its lower end in a flaring or funnel end 2, suitably supported by a bracket 3 or other form of supporting means. The upper end of the stack above the smoke box is curved in a reverse direction at 4, in order that the exhaust may be discharged in a perpendicular direction, as in the case of a straight smoke stack.

Adjacent to the funnel end 2 of the smoke stack, and in alinement therewith supported by suitable brackets 5 and 5^a, is a conical pipe 6, which I term a petticoat pipe, having a funnel or flaring end similar to and extending in the same direction as the funnel end 2 of the smoke stack 1. The pipe 6 and funnel end 2 are separated a slight distance for a purpose hereinafter made apparent.

Directed to the center of the petticoat pipe 6 is an upwardly extending exhaust pipe having a curved nozzle 7, separated a slight distance from said pipe. Surrounding the smoke stack 1 at the outward half of its curve, and extending from its lower end to a point preferably above the smoke stack, is a casing 8 eccentrically arranged, forming a spark chamber enlarged at one side and tapering downwardly to a point at the lower end of the stack, as best shown in Figs. 1 and 2. The side of the stack enclosed by the casing has cut therein a series of spiral slots or openings 9, provided with overhanging downwardly inclined deflector plates 10 at their upper edge, said slots and deflector plates forming traps for the sparks and cinders. The deflector plates project into the stack 100 and are preferably made integral therewith by cutting the metal forming the slots 9 at the bottom and side edges only and bending it back into the stack opening. At the upper end of the enlarged side of the spark 105 chamber a cinder pipe 11 leads back to the ash pan or fire box, following the curve of the boiler and provided near the point of its connection with the spark chamber with a constricted pass controlled by a damper 12 110

adapted to be regulated by a handle 13 upon the exterior. This pass is for the purpose of checking excessive flow of the exhaust gases.

The operation of the device is as follows:

- 5 When the locomotive is exhausting, the exhaust is conducted through the nozzle 7 and forced through the petticoat pipe 6 up the stack, carrying with it cinders and sparks drawn in by the draught caused thereby.
- 10 The cinders, sparks and other solid particles will hug the front wall of the stack and will be deflected by the plates 10 through the slots 9 together with a small percentage of the gaseous portion of the exhaust; and by
- 15 reason of their momentum and pressure behind will pass up the spark chamber 8 through the pipe 11 preferably to the fire box where they will be consumed by the fire. Any sparks which fail to pass in the
- 20 pipe 11 will drop back to the lower end of the spark chamber, and if not arrested in their descent by a subsequent exhaust, will fall out through the lower opening in the engine stack, thereby keeping the spark chamber
- 25 clear and open at all times.

The inclined arrangement of the slots 9 and deflector plates 10 forming the traps, centrifugally throws the solid particles to the enlarged side of the spark chamber and into 30 alinement with the spark pipe. With certain classes of fuel it may be found desirable to change the inclination of the traps, and in some cases to make them substantially horizontal. The sparks in passing from the

35 spark chamber to the spark pipe, will, by the centrifugal action, follow the outer curve of the pipe and permit the constricted portion controlled by the damper 12 to be so regulated as to eliminate a large percentage of

40 the exhaust gases. The casing forming the spark chamber is preferably constructed to be easily removed in order that the traps may be repaired or for other necessary purposes.

45 The precise embodiment of my invention is not material, provided its essential characteristics are employed as pointed out in the annexed claims.

Having thus described my invention I 50 claim as new and desire to secure by Letters Patent:

55 1. In a spark arrester, the combination of a reversely curved smoke stack having a flaring lower end, a conical pipe having a flaring end adjacent thereto and in alinement therewith, traps for the sparks formed by inclined slots and deflector plates at the outer side of the stack, a casing eccentrically surrounding the traps, and a spark pipe connected to the

60 upper end of the casing for the purpose described.

65 2. In a spark arrester, the combination of a curved smoke stack, a spark chamber eccentrically connected to the outward curved portion thereof, means carried by the stack

adjacent to the chamber for separating the sparks or cinders and discharging them therein, and means connected to the chamber for conducting the sparks to the fire box.

3. In a spark arrester, the combination of 70 a curved smoke stack having a flared lower end, a conical pipe adjacent thereto and in alinement therewith having a flared end, a spark chamber eccentrically surrounding the outward curved portion of the stack, means 75 carried by the stack adjacent to the chamber for separating the sparks and discharging them therein, and a pipe connected to the upper end of the chamber, having an adjustable constricted pass for the purpose de- 80 scribed.

4. In a spark arrester, the combination of 85 a reversely curved smoke stack extending into a smoke box, a spark chamber eccentrically carried at the outward curved portion thereof, means carried by the stack for separating the sparks and discharging them into the chamber, and a pipe connecting the upper end of the chamber, having a constricted pass and conducting the sparks 90 to the fire box.

5. In a spark arrester, in combination, a curved smoke-stack having a series of openings and passing therethrough at the outer curved side thereof whereby as cinders and 95 other solid particles are forced up the stack they will hug said outer curved side and pass through said openings on their upward movement.

6. In a spark arrester, in combination, a 100 curved smoke-stack having openings therein at the outer curved side thereof, and a casing connected to the stack surrounding said openings and forming a spark chamber whereby as cinders and other solid particles are forced 105 up the stack they will hug said outer curved side and pass through said openings on their upward movement to said spark chamber.

7. In a spark arrester, in combination, a curved smoke-stack having openings therein 110 at the outer curved side thereof, deflector plates over the openings, and a casing connected to the stack surrounding said openings and forming a spark chamber whereby as cinders and other solid particles are forced 115 up the stack they will hug said outer curved side and be deflected by said plates on their upward movement through the openings into said spark chamber.

8. In an engine, a smoke-box, an exhaust 120 nozzle therein, and a curved smoke-stack passing into the smoke-box in close proximity to the nozzle, said stack having openings therein at the outer curved side thereof whereby as cinders and other solid particles 125 are forced by the nozzle through the stack, they will hug said outer curved side and pass through said openings.

9. In an engine, a smoke-box, an exhaust 130 nozzle therein, a curved smoke-stack passing

into the smoke-box in close proximity to the nozzle, said stack having openings therein at the outer curved side thereof, and deflector plates over the openings whereby as cinders and other solid particles are forced through the stack by the nozzle, they will hug said outer curved side and will be deflected by said plates through said openings.

In testimony whereof I have signed my name to this specification in the presence of 10 two subscribing witnesses.
